Wichita, Kans., a corporation of Kansas**

Application June 22, 1954, Serial No. 31,100

Term of patent 14 years

(Cl. D48—24)

To all whom it may concern:

Be it known that we, Wilbur J. Townsend and Anthony M. Castello, citizens of the United States, residing at Wichita, county of Sedgwick, and State of Kansas, have invented a new, original, and ornamental Design for a Lantern, of which the following is a specification, reference being had to the accompanying drawing, forming a part thereof, in which:

Fig. 1 is a top plan view of a lantern showing our new design,

Fig. 2 is a side view in elevation,

Fig. 3 is a perspective view, and
Fig. 4 is a bottom plan view.

We claim:
The ornamental design for a lantern, as shown.
